[57] CLAIM

The ornamental design for a storage and display container, as shown and described.

DESCRIPTION

FIG. 1 is a perspective view of a storage and display container illustrating my new design;

FIG. 2 is a side view of the design shown in FIG. 1, the opposite side being substantially a mirror image thereof;
and,

FIG. 3 is a top view of the design shown in FIG. 1.
